FIG-5

FIG-6

FIGURE 1 is a front perspective view of the roll-top desk shown in open position;

FIGURE 2 is a rear perspective view of the roll-top desk shown in closed position;

FIGURE 3 is a rear elevational view of the roll-top desk looking from the rear of FIGURE 1 with the desk shown in open position;

FIGURE 4 is a rear elevational view of the roll-top desk similar to FIGURE 3, but showing the roll-top desk in closed position;

FIGURE 5 is a top plan view of FIGURE 4, and showing the roll-top desk in closed position; and

FIGURE 6 is a side elevational view of the roll-top desk.

The dominant features of my design reside in those portions shown in full lines on the drawings.

I claim:

The ornamental design for a roll-top desk, substantially as shown and described.
